UNITED STATES PATENT OFFICE.

JULIUS BRENDLE, OF ZURICH, SWITZERLAND.

WORKMAN'S TIME RECORDER.

Application filed August 1, 1921. Serial No. 488,895.

To all whom it may concern:

Be it known that I, JULIUS BRENDLE, a citizen of the Republic of Switzerland, residing at Zurich, Switzerland, have invented 5 certain new and useful Improvements in Workmen's Time Recorders; and I do hereby declare the following to be a clear, full, and exact description of the invention, such as will enable others skilled in the art to 10 which it appertains to make and use the same, reference being had to the accompanying drawings, and to letters or figures of reference marked thereon, which form a part of this specification.

15 This invention relates to improvements in workmen's time recorders and particularly to that kind of recording apparatus in which the means for actuating type-wheels are automatically thrown in and out of gear to 20 take into account intervals in the working time.

To control and record workmen's time by means of record cards on which the time recorded by a clock work is printed apparatus has already been proposed for the purpose of rendering superfluous a subsequent addition of the total working hours and in which a continuous recording of the working time is effected by an actuating 25 wheel (the "day"-wheel) which is driven by a clock work and which controls the duration of the ratchet movement of the type-wheels serving to print the time records on record cards. The ratchet movement of the 30 type-wheels has been effected by the intermediary of an electro-magnetic auxiliary device. Such devices are dependent on a source of electricity, further they cause a complicated construction and a delicate apparatus.

40 The present invention has for its object a workmen's time recorder in which the actuating wheel driven by a clock work causes an automatic throwing in or out of gear of the means for causing the ratchet movement of the type-wheels. According to the present invention the actuating wheel influences 45 mechanical controlling means which adjust a locking device. The locking device may 50 act upon the ratchet means adapted to impart a ratchet movement to said type-wheels and according to the adjustment of said locking device the ratchet means are operative or inoperative. The mechanical controlling means may comprise two cooperating 55 control levers one of which serving to

render operative the locking device for the ratchet means actuating the type-wheels and the other control lever being adapted to cut out said locking device.

60 Two constructional forms of the object of the invention are illustrated by way of example on the accompanying drawings, on which only the vital parts of the recorder serving to indicate the present invention are 65 shown. In the drawings:

Fig. 1 is an elevation of the apparatus, some parts being broken off;

Fig. 2 is a plan view of Fig. 1, in which several parts of the apparatus are omitted. 70

Fig. 3 shows a vertical section along line I—I of Fig. 1;

Fig. 4 illustrates for the greater part in section the type wheels;

Figs. 5, 6 and 7 are sections along lines 75 II—II, III—III and IV—IV respectively of Fig. 4.

Figs. 8—10 show details of the apparatus.

Fig. 11 is an elevation of a modified form 80 of the apparatus.

Fig. 12 is another elevation corresponding to that of Fig. 11 some parts being shown in different operative positions.

Fig. 13 is a side view of Fig. 11.

Fig. 14 shows a detail of the modified apparatus illustrated in Figs. 11—13. 85

Figs. 15 and 16 illustrate a detail in side view and plan view of the first constructional example.

Figs. 17 and 18 are front and side elevations respectively of the complete apparatus according to the modified construction, the front wall of the casing in the respective elevations being cut away.

Fig. 19 is a drawing of a form of workman's card to be used in the machine.

Referring to the first constructional example illustrated in Figs. 1—10, 1, 2, 3 and 4 denote four frame plates rigidly connected to each other. On the barrel-arbor 5 the 100 actuating wheel 6 is fixed and rotated by means of a clock-work 7. The wheel 6 performs one complete revolution every 24 hours, it is therefore also called the "day"-wheel. The wheel 6 is provided with a number of cams 8 which serve to actuate a two-armed lever 11 (shown in detail in Figs. 9 and 10) rotatably mounted on an axle 10 and loaded by a tension spring 9. The two-armed lever 11 which forms a mechanical 105 controlling means, is provided with a toothed segment 12 meshing with a pinion 110

13. Upon a rotary movement of the wheel 6 in the direction of the arrow indicated a cam 8 comes into engagement with the control lever 11 and causes the latter to swing 5 in the direction indicated by the arrow in Fig. 1, whereby the toothed segment 12 imparts a rotary movement to the pinion 13; the locking device 14 (Fig. 8) which is operatively connected to the pinion 13 by 10 means of a coupling working in one direction only and formed by a pawl 13'' and ratchet wheel 13' does not take part in said rotary movement of the pinion. The locking device 14 consists of a disc provided 15 with five stop pins 15 of equal length and of a second disc rigidly connected to the former and provided with three stop pins 16 (Fig. 3), two of which are of a greater length than the third of said pins. Upon 20 a cam 8 having passed the control lever 11 the latter is caused to swing back into its initial position by the action of the spring 9. During this movement the locking device 14 is turned by the action of the pinion 25 13 and pawl 13'' and ratchet wheel 13'. The locking device 14 is secured in this turned position by a plate spring 17 entering into one of the notches provided on the circumference of the one disc of said device. Upon 30 the return movement of the control lever 11 into its initial position a lateral projecting lug 18 (Fig. 9) provided on said lever bears against one of said stop pins 15 and limits thus the rotary movement of said locking 35 device.

19, 20 and 21 are three two-armed levers acting as propelling-pawls to the ratchet wheels 22, 23 and 24 respectively, said 40 wheels being rigidly connected to type wheels 25, 26, 27 respectively used for recording the working time, each of the type-wheels being provided around its circumference with the figures 0—9, twice in succession. The pawls 19—21 are independently 45 of each other rotatably mounted on a bolt 28 (Fig. 1), the latter being carried in a forked holder 29 swingably mounted about the axle 30 which is carried in the shields 2 and 3. A tension spring 31 is operatively 50 connected to each pawl 19—21 and presses the latter against the corresponding ratchet wheel. The tension springs 31 are connected at their other ends to the holder 29. A cross arm 21' of the pawl 21 abuts against the 55 pawl 20. A stop lever 32 cooperates with each pawl 19—21; the three stop levers 32 are mounted on a common bolt 33 and are pressed against the corresponding ratchet wheel 22, 23 and 24 respectively by the 60 intermediary of a tension spring 34 provided for each pawl and said stop levers are lifted out of engagement with said ratchet wheels by the corresponding pawl abutting with its upper end against the facing 32' of the stop 65 lever upon the swinging motion of the

holder 29. The two ratchet wheels 22, 23 are fitted with laterally arranged discs 35 and 36 respectively which are provided with two notches 35' and 36' respectively arranged diametrically opposite to each other 70 and which are influenced by the tooth of the adjacent pawl 20 and 21 respectively.

A ratchet wheel 37 actuated at certain intervals from the clock-work 7 through the interposition of an auxiliary mechanism, 75 imparts at said intervals, for example every six minutes a swinging motion (in a clockwise direction in Fig. 1) to the holder 29 by the intermediary of a lever 38 fixed on the axle 30 which lever is in engagement 80 with the wheel 37 by means of a laterally projecting pin 38'. Upon the completion of said swinging motion the holder 29 returns in its initial position by the action of a tension spring 39 (not shown in Fig. 1). Each 85 swinging movement of the holder 29 causes the propelling pawl 19 of the operative ratchet device to turn the ratchet wheel 22 and thereby the type-wheel 27 by the amount of one unit; the corresponding stop 90 lever 32, after the completion of said ratchet movement, comes into engagement with the teeth of the ratchet wheel 22 and thus secures the type-wheel 27 in its position. When the type-wheel 27 serving for registering the units (in this case one tenth of 95 an hour) has been actuated nine times, then the tooth of the pawl 20 belonging to the adjacent type-wheel 26 enters into the one notch 35' of the lateral disc 35 of the ratchet 100 wheel 22 so that upon the following swinging motion of the holder 29 the two pawls 19, 20 become operative, i. e. both type-wheels 27, 26 are rotated by one pitch unit, the type-wheel 26 registers the tens (i. e. 105 the hours). When the type-wheel 26 registering the hours has been actuated nine times the tooth of the pawl 21 enters the notch 36' of the lateral disc 36 of the ratchet 110 wheel 23 and is now in an operative position with regard to ratchet-wheel 24. On the subsequent swinging motion of the holder 29 the pawl 21 actuates the ratchet wheel 24 and causes thus a turning motion 115 of the type wheel 25 through the extent of one pitch-unit (a hundreds); the pitch-unit of this type wheel corresponds to ten hours.

As long as the figure 9 of the two type wheels 26 and 27 is not in the position in which it can be impressed on a record card, the laterally projecting arm 21' of the pawl 21 prevents an engagement of the pawl 21 with the ratchet wheel 24.

The provision of the ten hours type wheel 25 enables to record the working time of 125 for instance two weeks provided the normal working time per week does not exceed 50 hours. The record-cards (indicated in Fig. 18 in chain-dotted lines) are inserted into a slot 80 (Figs. 17, 18) in a known 130

manner and are therein guided to the front of the type wheels for the purpose of having the time record printed on them. A coloured ribbon 81 is arranged in front of the type wheels and a spring retracted printing lever 82 is freed from a catch on the operating lever 83, upon the latter being depressed.

During the mid-day interval the type-wheels 25, 26, 27 are not actuated as in the meantime the long stop pin 16 has automatically and through the intermediary of the control lever 11 been moved against the pawls 19, 20, 21 and has caused the latter to perform a turning motion around the bolt 28 whereby they are brought into an inoperative position, i. e. the pawls are now thrown out of engagement with the ratchet wheels 22—24.

When now the time for resuming work has come then the control lever 11 glides off the cam 8 of the actuating wheel 6 and causes a further turning movement of the locking device 14. The pawls 19—21 are thereby thrown in gear and the type-wheels 25—27 are again subjected to the influence of the pawls 19—21, and are actuated by the latter as long as the ratchet action is maintained.

After the termination of the normal daily working time the short stop pin 16 of the locking device 14 comes into its operative position, after the locking device 14 is influenced by the control lever 11, which has been actuated by a cam 8 of the actuating wheel 6 which has meanwhile advanced to said position. The short stop pin 16 prevents the action of the pawl 21 and thereby a step-by-step movement of the type-wheel 25 recording the hundreds of units. The two pawls 19, 20 may continue to work during the next 10 hours and may actuate the type wheels 27, 26 to indicate hours and tenths of hours in order to record an eventual over-time, thereafter an operative action of the control lever 11 on the locking device 14 causes the longer stop pin 16 to become operative and the three pawls 19—21 to become inoperative in the manner described above. It is evident that the two type wheels 26 and 27 have the same figure in the printing position after the lapse of the ten hours over-time, as at the end of the normal daily working time. As in the mean-while an actuating of the type wheel 27 recording the hundreds has been prevented the indication of the type wheels 25—27 upon resuming the work the following day is the same as that at the end of the normal daily working period.

Upon the re-commencement of the working period the locking device 14 is so adjusted by the wheel 6 that the three pawls 19, 21 are operative so that the type-wheels

25—27 record the working time until the operation of the pawls is interrupted and the latter are thrown out of gear in consequence of an interval in the working.

In order to bring into prominence the over-time on the cards on which the records are printed a circular disc 40 is provided on the apparatus which has a special mark on its circumference for instance a plus-sign. The circular disc 40 is provided with an arm 40' that projects into the plane of turning of a projecting part 41 fitted to the locking device 14 (Fig. 8), a plate spring 42' bearing against said arm 40'. At the end of the normal daily working time, as soon as the short stop pin 16 of the locking device 14 causes the pawl 21 to be inoperative, a turning motion is imparted to the circular disc 40 by the projecting part 41 to such an extent that the mark, i. e. the plus-sign, is in the position in which it can be recorded or printed on a card. As the locking device 14 is only adjusted again after the ten hours (the over-time) have passed, the mark remains during said period in the printing position, so that any record printed during said period bears said mark or plus-sign; in this way the total amount of the over-time can easily be arrived at. Upon the subsequent turning or adjustment of the locking device 14 the circular disc 40 is turned back into its initial position by the action of a plate spring 42 and remains in that position until after it is desired of the apparatus to record over-time.

The circular disc 40 provided with the sign for indicating the over-time is rotatably mounted upon a sleeve integral with a type-wheel 43 (Fig. 4) serving to record or print the months. A plate spring 44 secures the type-wheel 43, which is turned by hand, in its momentary position. 45 denotes a type-wheel for marking the working days according to their ordinal numbers. The type-wheel 45 is actuated by the intermediary of a ratchet wheel 46 and a pawl 47 cooperating with the latter. The pawl 47 has its fulcrum on a four-armed member 49 (shown in detail in Fig. 15) and is pressed against the ratchet wheel 46 by means of a spring 50. The four-armed member 49 is swingably mounted on a bolt 51 fixed in the frame plate 2, one of its arms 52' projecting into the path of a pin 52 provided on the wheel 6. Upon each revolution of the wheel 6 the member 49 is turned by the action of said pin 52 and against the action of a tension spring 53, whereafter said spring causes the member 49 to return into its position of rest. Thereby the pawl 47 shifts the type-wheel 45 by the amount of one pitch-unit. A pawl 54 which is swingably mounted on the bolt 51 is pressed against the ratchet wheel 56 by the action of a tension spring 55, 130

the ratchet wheel 56 being rigidly connected to the ratchet wheel 46; thus the pawl 54 secures the type-wheel 45 in its momentary position.

5 The swinging motion of the member 49 causes, through the intermediary of a pawl 57 linked to another arm (the left hand arm in Figs. 1 and 15) of said member, a turning motion of a disc shaped organ 58, on which 10 a ratchet wheel 60 is provided, against which the pawl 57 is pressed by a plate spring 59. A pin 61 fixed to the member 49 limits the ratchet motion of the pawl 59 by entering a notch of the organ 58. The abutment of the 15 pin 61 against the organ 58 determines at the same time the position of rest of the member 49. The organ 58 is provided with seven notches which correspond to the number of days in a week; a plate spring 62 is 20 adapted to enter into said notches and secures the organ 58 in its momentary position.

The organ 58, which performs one revolution per week, is provided at its one side with 25 a guide facing 58' against which a lateral projection on the boss of the control lever 11 is pressed by means of a compression spring 62' (Fig. 2). The organ 58 causes an axial displacement of the control lever 11 relatively to the wheel 6. Thus the control lever 11 is shifted into the path of a group of 30 cams 8 in dependency upon the day of the week, at days with the same working time the same group of cams 8 is operative. The 35 highest point of the guide facing of the organ 58 becomes operative 10 hours after the end of the normal working time on a Saturday, whereby the control lever 11 is brought out of the path of the cams 8, so 40 that the wheel 6 performs its turning motion without causing a ratchet motion of the type-wheels 25-27 whilst on the other hand the type-wheel 45 with the ordinal numbers of the days is still actuated by the pin 52 45 and the member 49. On Monday morning, when the normal working time starts again, the ratchet movement of the type-wheels 25-27 sets in again, as in the mean time the highest point of the guide facing 58' of the 50 organ 58 has passed the projection on the boss of the control lever 11, whereby the latter is brought again into the path of the cams 8 and the pawls 19-21 are operative again.

As may be seen from Fig. 1 the outermost 55 point of the cam 8' of the wheel 6 has a greater distance from the center of the wheel shaft 5 than the remaining cams. This larger cam 8' imparts therefore a swinging motion of a greater magnitude to the control lever 11 and a correspondingly greater turning motion of the locking device 14. The cam 8' serves for example for the adjustment of the locking device 14 on Saturday, when the normal working time finishes 60 earlier, for instance at mid-day, than on

other days. In this manner the locking device 14 is so adjusted or turned, that instead of the long stop pin 16, which becomes operative on the normal adjustment of the locking device 14, the short stop pin 16 becomes operative and the two type wheels 27, 26 are then actuated for the purpose of recording an eventual over-time.

The adjustable arrangement of the cams on the wheel 6 enables to bring the moment of their operation in conjunction with the working periods, so that, as the cams may be arranged in several planes, a great variety of operations result. When a holiday occurs in a working week the means for actuating the type-wheels 25-27 are cut out by hand by moving the control lever 11 so that two longer stop pins 16 are out of operation with the pawls 19-21 and by bringing the control lever 11 into such a position that it is not acted upon by the cams. 75

Thus it will be seen that the locking device 14 controlled by lever 11 obtains a clock-wise step-by-step movement from the unidirection coupling device 13', 13". 80

The extent of this movement of the locking device 14 is dependent upon the distances of the outer ends of the cams 8, 8' from the centre of the day wheel.

In Fig. 1 none of the pins 16 of the locking device 14 are in operating position, as all three pawls 19, 20 and 21 are free and engage the respective ratchet wheels, 22, 23 and 24 of their type wheels 25, 26, 27. 95

In Figs. 1 and 3, the short pin 16 is uppermost and in order to complete a rotation the locking device shall make five steps in accordance with its five peripheral notches successively engaged by spring 17. 100

The locking device assumes the position shown in Fig. 1 before the noon recess.

By reason of one of the cams 8 coming into action at noon, the long pin 16 at the right of the short pin comes into operative position and all three pawls 19, 20 and 21 are moved out of operative relation, so that no time will be registered during this period. At the end of the noon period the locking device 14 is moved another step, releasing all three of the pawls for proceeding with time registration. 110

The next step occurs at the end of the work day, and the short pin 16 comes into operation and releases the pawl 21 or the hundred pawl whose movement occurs every ten hours, and the other two pawls 19 and 20 remain operative for a further period of ten hours, so that any over-time may be registered by wheel 26 for the hours and 27 for one-tenth hours, during which time the + sign remains in printing position. 120

At the end of this overtime stretch of ten hours, the locking device makes a fourth step, and all three pawls are withdrawn 125

from the ratchet wheels by the long pin 16 at the other side of the short pin.

Next morning, at the beginning of the work day, a fifth step is made, and all pawls 5 again released and all the registering wheels begin to register the new day. The units and tens wheels are at zero, having moved through a ten hour period and the ten hour wheel begins to accumulate and 10 add on the previous day the hours and fractions of hours of the new day.

A workman's card, such as shown in Fig. 19 is placed in the machine and stamped at the beginning and end of the day, if he 15 works by day work, or at the beginning and end of the week.

The card is divided by horizontal lines A, which are intersected by other lines to form columns B and C, leaving a space at 20 the left and top for such data or notations as may be desired.

For over time he registers in column B each day at the end of the day, and then at the end of the overtime.

25 Assume the week began 4 Dec. the machine then is at zero, and he registers at the end of the week 9 Dec., the difference between the two in column C, which is written in by hand opposite the two dates, 30 shows a 48 hour week. Suppose there is over-time on Dec. 9, then the workman prints the time and date his overtime begins 9+Dec.485 and also when he finishes 9+Dec. 495, and the difference is also written 35 ten in column C.

The second constructional example of the recorder illustrated in Figs. 11-14 differs from the previously described example in as much as the controlling arrangement influenced 40 by the wheel carrying the cams is provided with two control levers whereas only one such lever has been provided in the first example; one of said control levers serving to cut in the means for stopping the 45 ratchet motion of the type-wheels and the other to cut out said means.

The wheel carrying the cams 8, is as in the previous example, fixed to the arbor 5 of the clock-work and is provided with two 50 rims 6 and 6', to which are fixed the cams 8; only one such cam on each rim being shown in Figs. 11 and 12. The cams are fixed by means of set screws the heads of which glide in circular grooves provided in 55 said rims so that the cams can be adjusted along the circumference of the wheel rims 6 and 6'. The acting faces of the cams fixed to a rim are not in the same plane of turning. The cams of each rim 6 and 6' respectively 60 serve to actuate control levers 11 and 11' respectively; the latter being rotatably mounted on a common axle 10 and are loaded by tension springs 9. The two control levers can be shifted in the axial direction on the axle 10. A compression

spring 62' mounted on the axle 10 causes the control lever 11 to be pressed in its lateral direction against the organ 58, by which organ the adjustment of the control levers 11 and 11' in the axial direction relatively to the planes of turning of the cams is effected, in correspondence with the day of the week as has been described in the first constructional example.

14 denotes again the locking device effecting the operative and inoperative position of the pawls actuating the type-wheels. The locking device 14 is provided with a toothed segment and an arm 16' carrying a locking pin 16. A forked holder 29 swingably mounted on the axle 30 is provided with an axle 28 mounted in the forked ends of said holder, the two-armed actuating lever 17 is turnably arranged on the axle 28. One arm of the actuating lever 17 is provided with a cross-piece 17' on which three teeth of different height for actuating the three ratchet wheels 22, 23, 24 are formed. The ratchet wheels are also rigidly connected to type wheels bearing figures in the 90 manner described hereinbefore; the latter being not shown in the Figs. 11-13. A tension spring 39 (Fig. 15) operatively connected to the rear end of the holder 29 holds the latter in its normal position in 95 which the lever 17 is inoperative. A tension spring 31 connects the lever 17 resiliently to the holder 29. A disc 40 provided with a plus-sign or another mark for recording over-time is arranged and actuated 100 by its arm 40' which cooperates with the forked end of an arm 41, the latter being rigidly connected to the locking device 14. The latter is provided at the opposite side with a double arm 65, 66. To the arm 65 105 a tension spring 67 is operatively connected which tends to hold the locking device 14 in its normal position, in which the arm 66 abuts against a pin 68 (Fig. 1) fixed in the shield 3.

In the bent up portion of a stationary plate 69 a pawl 70 is fulcrumed which cooperates normally with the toothed segment of the locking device 14, a spring 71 pressing the pawl into engagement. The pawl 70 is provided in its upper portion with a pin 72. On the control lever 11' a lever 73 is rotatably carried which is pressed against a pin 75 of the control lever by a spring 74 and is thus secured in its normal position. The control lever 11 carries a pawl 76 which is normally pressed by means of a spring 77 (Fig. 4) against a pin 78 fixed to the control lever.

In Fig. 1 the locking device 14 is shown 125 in its inactive position in which it has no influence on the movements of the actuating lever 17. The holder 29 is swung by a certain amount at definite intervals, for instance after every six minutes, by means ac-

tuated by the clock work (not shown in Figs. 11-13). This swinging motion occurs in a clockwise direction in Figs. 1 and 2. The holder 29 returns then under the influence of the tension spring 39 into its initial position, whereby the lever 17 actuates the ratchet wheel 22 and its corresponding type-wheel recording the units by one pitch-unit, a stop lever (not shown) secures the ratchet wheel 22 in this position until the next ratchet movement is imparted to the latter. The other ratchet wheels and the type wheels connected thereto are operated and the time recorded in the manner described in the previous example.

The actuating movement of the type wheels is interrupted by the automatically occurring operation of the locking device 14, the latter being effected as follows:

By one of the cams 8 abutting against the control lever 11 upon the turning of the wheel 6 in the direction of the arrow indicated in Fig. 1, said control lever 11 is turned so that its pawl 76 is moved in a downward direction and glides thereby along the toothed segment of the locking device. As soon as the control lever 11 has passed the highest point of the cam 8 the former is returned into its initial position, by the action of the tension spring 9. On this return movement the pawl 76 cooperates with the toothed segment of the locking device 14 and turns the latter from the position shown in Fig. 1 into that shown in Fig. 2 in which latter position the locking device 14 is secured by the pawl 70. Now the stop pin 16 of the arm 16' contacts with the actuating lever 17 and turns the latter so that the teeth of the portion 17' are moved away from the ratchet wheels 22-24. The stop pin 16 against which the actuating levers 17 are pressed by the spring 31 prevents said lever from operating the ratchet wheels, as the toothed part of said lever cannot come into engagement with the ratchet wheels 22-24 when the holder 29 performs its periodic swinging movement.

Upon the further rotary movement of the wheel 6 carrying the cams the cam 8 cooperating with the second control lever 11' engages with the latter and causes it to be swung out of its normal position so that the lever 73 is moved in a downward direction. During this movement the lever 73 glides past the pin 72 of the pawl 70 and the upper end of said lever is now vertically below said pin. At the end of the working interval the control lever 11' has passed the cam 8 and is returned into its initial position by the action of the tension spring 9. By this return movement the levers 73 impacts against the pin 72 and causes a turning motion of the pawl 70 which thereupon disengages the teeth of the locking device 14.

In consequence thereof the locking device 14 is turned back into its inactive position (Fig. 1) by the action of the tension spring 67 connected to the double arm 65, 66, in which position the latter bears against the pin 68 and moves the teeth of the actuating lever 17, 17' into engagement with the ratchet wheels. Upon a small displacement of the pawl 70 the lever 73 glides off the pin 72 and the pawl 70 is brought again by the action of spring 71 into engagement with the toothed segment of the locking device 14.

The above described motions are repeated as soon as the control levers 11 and 11' are actuated by the cams 8 for the purpose of cutting in and out the locking device 14 and thereby the ratchet movement of the type wheel. The actuating of the two control levers may be effected one shortly after the other by adjusting the cams in appropriate positions on the wheel 6 or between the actuating of the two control levers a longer period may elapse and it is thus rendered possible by a single adjustment of said cams to interrupt the ratchet motion imparted to the type wheels for a longer or a shorter period in accordance with the intervals of the working time and to generally adapt the recorder to any conditions given by the actual working time. It will thus be seen that all overtime work may be registered directly on a registering apparatus of the kind described, that is to say without any special manipulation of the mechanism of the apparatus; the driving mechanism of the time type wheels is so mechanically controlled by the cam or stop wheel according to this invention, that after the completion of the normal daily working time, it is first only partially thrown out of operation, so as to be able to register, during a certain interval of time, all overtime work which is indicated by an automatically moved recording character or symbol held in the printing position during this interval of time, after which the ratchet driving mechanism (19-21) is entirely prevented from performing its driving action until again completely thrown into operation.

All overtime work is separately registered, that is to say, without altering the sum of the working hours registered by the type wheel mechanism at the end of the normal daily working time, as long as the ratchet driving mechanism has not been released for complete action, i. e., the recommencement of the normal working time.

In order that such a change in the number of hours registered may not take place, during the restricted action of the feed mechanism (overtime work) only the type wheel of the units (tenths of hours) and that of the tens (hours) is allowed to feed and that during an interval of time of ten hours, after which these two type wheels have again

reached a position in which they once more indicate the number of hours registered at the conclusion of the normal daily working time.

5 I claim:

1. In a workmen's time recorder having an operating train of gears, time type wheels and ratchet driving mechanism therefor, in combination with a stop wheel mechanically driven to render one of the type wheels inoperative at the expiration of a normal working day; a character indicating over-time alternately brought into operative position at the expiration of said normal 15 working day while maintaining the operation of the remaining type wheels.

2. In a workmen's time recorder having time mechanism, time type wheels and ratchet mechanism driving the type wheels 20 from said time mechanism, in combination with a stop-wheel mechanically driven to render one of the type wheels inoperative at the end of a normal working day; a character indicating over-time mechanically 25 brought into operative position at the end of a normal working day and returned to inoperative position after a pre-determined time, and mechanism to automatically discontinue the driving of the time type wheels 30 during a non-working day.

3. In a workmen's time recorder, in combination, a clockwork, a wheel driven by said clock-work carrying a number of cams spaced according to the duration of working periods and arranged in different planes of rotation, mechanical controlling means adapted to be influenced by said cams, an automatically actuated organ for bringing said controlling means into the path of said 40 cams, a locking device operatively connected to said controlling means and adjusted in different positions by the latter, recording type-wheels, and means for imparting a ratchet movement to said recording type-wheels operatively connected to said locking device which means are thrown in and out of gear in accordance to the position into which said locking device is adjusted.

4. In a workmen's time recorder, in combination, a clockwork, a wheel driven by said clock-work and carrying a number of cams spaced according to the duration of working periods and arranged in different planes of rotation, a two-armed lever adapted to cooperate with said cams, a rotating member provided with a guide facing with which said two-armed lever is in engagement for adjusting said lever into said different planes of rotation and adapt it to 55 cooperate with said cams, a rotatable locking device operatively connected to said two-armed lever and adjusted in different angular positions by the latter, recording type wheels, and means for imparting a ratchet movement to said recording type wheels 60

operatively connected to said locking device, which means are thrown in and out of gear in accordance to the angular position into which said locking device is adjusted.

5. In a workmen's time recorder, in combination a clock-work, a wheel driven by said clock-work and carrying a number of cams spaced according to the duration of working periods, a two-armed lever influenced by said cams, a rotatably arranged locking device provided with stop pins of different lengths, said device being operatively connected to said two-armed lever and adjusted in different angular positions, recording type wheels, and means for imparting a ratchet movement to said recording type wheels operatively connected to said locking device, which means are thrown in and out of gear wholly or partly in accordance to the length of the operative stop pin of the locking device so that over-time can be recorded. 70 75 80

6. In a workmen's time recorder, in combination, a clock-work, a wheel driven by said clock-work and carrying a number of cams spaced according to the duration of working periods and arranged in different planes of rotation, a two-armed lever influenced by said cams, a rotating organ provided with a guide facing for bringing said two-armed lever into the path of said cams, a locking device operatively connected to said two-armed lever and adjusted in different positions by the latter, recording type wheels, means for imparting a ratchet movement to said recording type-wheels operatively connected to said locking device, which means are thrown in and out of gear in accordance to the position into which said locking device is adjusted, a type-wheel for indicating the ordinal number of a day, and rocking means for actuating the last mentioned type wheel and said rotating organ. 90 95 100

7. In a workmen's time recorder, in combination, a clock-work, a wheel driven by said clock-work and carrying a number of cams of different radial height spaced according to the duration of working periods, a two-armed lever influenced by said cams, a rotatably arranged locking device operatively connected to said two-armed lever and adjusted in different angular positions by the latter, recording type-wheels, means for imparting a ratchet movement to said type-wheels operatively connected to said locking device which means are thrown in and out of gear in accordance to the angular position into which said locking device is adjusted, and means for distinguishing over-time records moved into the printing position by 110 115 120 125 said locking device.

8. In a workmen's time recorder, in combination, a clock-work, a wheel driven by said clock-work and carrying a number of cams of different radial height spaced ac- 130

- cording to the duration of working periods, a two-armed lever influenced by said cams, a rotatably arranged locking device operatively connected to said two-armed lever and 5 adjusted in different angular position by the latter, recording type-wheels, a propelling pawl to each type-wheel, a common holder to said pawls swingably mounted and actuated periodically from the clock-work for 10 imparting the ratchet movement to said type-wheels, the pawls being thrown in and out of gear in accordance with the angular position of said locking device.
9. In a workmen's time recorder, in combination, a clock-work, a wheel driven by 15 said clock work and carrying a number of cams spaced according to the duration of working periods, two control levers adapted to be influenced by said cams, a locking 20 device operatively connected to said control levers and adjusted in different positions by the latter, recording type wheels and means for imparting a ratchet movement to said recording type wheels operatively connected to said locking device which means are thrown in gear by one of said control levers adjusting the position of said locking device and are thrown out of gear by 25 the other of said control levers adjusting 30 the position of said locking device.
10. In a workmen's time recorder, in combination, a clock-work, a wheel driven by 35 said clock work and carrying a number of cams spaced according to the duration of working periods, two control levers adapted to be influenced by said cams, a turnable locking device operatively connected to said control levers, a pawl provided on the one of said control levers for turning the locking 40 device into its operative position, means for securing said locking device in said position until they are released by the second control lever for causing the locking device to return into its inoperative position, recording type-wheels and means for imparting 45 a ratchet movement to said recording type wheels which means are thrown in and out of gear on the locking device becoming operative and inoperative.
- 50 11. In a workmen's time recorder, in combination, a clock-work, a wheel driven by 55 said clock work and carrying a number of cams spaced according to the duration of working periods, two control levers adapted to be influenced by said cams, a turnable locking device operatively connected to said control levers, a pawl provided on the one 60 of said control levers for turning the locking device into its operative position, means for securing said locking device in said position, a member swingably mounted on the second control lever adapted to release the means for securing said locking device and causing said device to return into its inoperative position, recording type wheels and means for imparting a ratchet movement to said recording type wheels which means are thrown in and out of gear on the locking device becoming operative and inoperative.
- 65 12. In a workmen's time recorder, in combination, a clock-work, a wheel driven by 70 said clock work and carrying a number of cams spaced according to the duration of working periods, two control levers adapted to be influenced by said cams, a turnable locking device provided with a toothed part and operatively connected to said control levers, a pawl provided on the one of said control levers and adapted to engage with said toothed part of the locking device for turning the latter into its operative position, means adapted to engage with said toothed part for securing the locking device in its operative position, means for causing a release of the locking device actuated by 75 the second control lever, recording type wheels, and means for imparting a ratchet movement to said recording type-wheels which means are thrown in and out of gear on the locking device becoming operative and inoperative.
- 80 13. In a workmen's time recorder, in combination, a clock-work, a wheel driven by 85 said clock-work and carrying a number of cams spaced according to the duration of working periods, two control levers adapted to be influenced by said cams, a propelling pawl for imparting a ratchet movement to said type-wheels by the pawl being provided with a number of teeth co-acting with 90 ratchet wheels each rigidly connected to the corresponding type-wheel, the pawl being brought into engagement with said ratchet wheels upon the position of the locking device being adjusted by one of said control levers and the pawl being brought out of engagement with said ratchet wheels upon 95 the locking device being turned into its operative position by the action of the second control lever.
- 100 In testimony that I claim the foregoing as my invention, I have signed my name.
- 105 JULIUS BRENDLE.
